UNITED STATES PATENT OFFICE.

WILLIAM McCLOSKEY, OF NEW ORLEANS, LOUISIANA, ASSIGNOR OF ONE-HALF TO GODFREY KOPP, OF SAME PLACE.

DEVICE FOR OPENING AND CLOSING RAILWAY-SWITCHES.

SPECIFICATION forming part of Letters Patent No. 390,181, dated September 25, 1888.

Application filed January 4, 1887. Renewed August 21, 1888. Serial No. 283,366. (No model.)

To all whom it may concern:

Be it known that I, WILLIAM McCLOSKEY, a citizen of the United States of America, residing at New Orleans, in the parish of Orleans 5 and State of Louisiana, have invented certain new and useful Improvements in Devices for Opening and Closing Railway-Switches, of which the following is a specification, reference being had therein to the accompanying drawings.

My invention relates to an improvement in automatic railway-switches, which will be fully understood from the following description, taken in connection with the annexed drawings, in which—

Figure 1 is a top view of the improved switch. Fig. 2 is a vertical section through Fig. 1 in the plane indicated by dotted line xx thereon. Fig. 3 is an enlarged top view of the 20 switch-head chair, showing the ends of three rails bearing thereon. Fig. 4 is a top and side view of one of the wheels used on the locomotive to actuate the switch-rails.

Referring to the annexed drawings by letter, A A' A' A' designate the main-track rails, which are rigidly spiked down upon the cross-ties R, that may be secured to longitudinal 25 sleepers P.

B B designate the side-track rails, the ends 30 of which, and also the ends of the switch rails C C, are supported upon switch-head chairs S S'.

C C designate the laterally-movable switch-rails, which are connected together by tie-rods 35 D D. One of the switch-rails is pivoted at H to a cross-tie, and the other switch-rail is free to slide endwise between parallel guide-extensions I I of one of the main-track rails, A'. The free ends of these switch-rails are 40 supported upon the two switch-head chairs S S'. Both of these chairs have raised side flanges, and the chair S is recessed at a a to receive tenons formed on those ends of the rails A B which rest upon it.

E E designate two horizontal levers vertically pivoted to blocks J J outside of the rails

A' A' and supported upon plates g g. These levers are connected by links or chains K K to the switch-rails C C, and they are also connected by chains F F to the vertically-movable ends of two spring-bars, L L, arranged parallel to the rails A' A', and rigidly secured to a cross-tie, O. The chains F pass through apertures in the necks of the rails A' A' and over pulleys p therein. (Shown in Fig. 2.) These 55 bars L L are supported upon coiled springs N N, and they have secured upon them beveled blocks M M, slightly raised above the plane of the track.

For the purpose of actuating the switch-rails 60 to shift a train from the main track upon a side track, or to shift the switch from a side track into line with the main track, I employ rollers V, (shown in Fig. 4,) which are vertically adjustably applied to the locomotive and 65 suitably placed under control of the engineer. These rollers are so arranged relatively to the blocks M M on the spring-bars L that when either one of said rollers is depressed it will 70 depress a spring-bar L and shift the switch to the desired position.

What I claim is—

1. The combination, with the main and side track rails, of connected switch-rails, one of which is provided at H and the other arranged 75 to move between guides I I, the switch-head chairs, levers connected to said switch-rails, the vertically-movable spring-bars L, provided with beveled blocks, and the flexible connections F of these bars passing over pulleys p and connected to said levers, all constructed and adapted to operate substantially 80 as described.

2. The recessed switch-head chair S, in combination with the rails A B, having tenons on 85 their ends fitted into said recesses, as described.

In testimony whereof I affix my signature in presence of two witnesses.

WILLIAM McCLOSKEY.

Witnesses:

GEORGE J. YENEWINE,
HENRY J. RHODES.
